US00D561650S

(12) United States Design Patent (10) Patent No.: US D561,650 S
(45) Date of Patent: * Feb. 12, 2008

(54) ROLLATOR

(75) Inventors: John Owens, Sheffield, OH (US); John Lescher, Sheffield Village, OH (US); Kevin Wysocki, Grafton, OH (US); Robert R. Bly, Wellington, OH (US)

(73) Assignee: Invacare Corporation, Elyria, OH (US)

() Term: 14 Years

(21) Appl. No.: 29/197,540

(22) Filed: Jan. 16, 2004

Related U.S. Application Data

(63) Continuation-in-part of application No. 09/977,122, filed on Oct. 12, 2001, now Pat. No. 7,040,637.

(51) LOC (8) Cl. 12-12

(52) U.S. Cl. D12/130

(57) CLAIM

The ornamental design for an rollator, as shown and described.

DESCRIPTION

FIG. 1 is a perspective view of a rollator showing my new design;

FIG. 2 is a left side view thereof;

FIG. 3 is a front view thereof;

FIG. 4 is a right side view thereof;

FIG. 5 is a rear view thereof;

FIG. 6 is a top view thereof;

FIG. 7 is a bottom view thereof; and,

FIG. 8 is a front perspective view thereof.

The portions of the Figures shown in phantom lines are not part of the claimed design but are for illustration only.

1 Claim, 5 Drawing Sheets
